UNITED STATES PATENT OFFICE.

WILLIAM B. LONGEST AND PHILIP S. LONGEST, OF LOUISVILLE, KENTUCKY.

DUMPING-VEHICLE.

1,079,780.

Specification of Letters Patent. Patented Nov. 25, 1913.

Application filed March 10, 1913. Serial No. 758,403.

To all whom it may concern:

Be it known that we, WILLIAM B. LONGEST and PHILIP S. LONGEST, of Louisville, in the county of Jefferson and State of Kentucky, have invented certain new and useful Improvements in Dumping-Vehicles; and we do hereby declare the following to be a full, clear, and exact description of the invention, such as will enable others skilled in the art to which it appertains to make and use the same.

This invention relates to improvements in dumping vehicles and more particularly to such as employ a side-dumping body comprising a plurality of dumping bins or compartments,—the present invention being designed as improvements upon that for which Letters Patent No. 1,013,789 were granted to W. B. Longest on the 2nd day of January 1912.

One object of the present invention is to provide simple and efficient means for dumping the bins or compartments at either side of the vehicle.

A further object is to provide a dumping wagon comprising a plurality of body units, in which said body units may be dumped either singly or collectively or in groups.

A further object is to provide simple and efficient operating mechanism and means for automatically controlling the operation of said operating mechanism when the same is power actuated.

With these and other objects in view, the invention consists in certain novel features of construction and combinations of parts as hereinafter set forth and pointed out in the claims.

In the accompanying drawings; Figure 1 is a side elevation of a dumping wagon embodying our improvements; Fig. 2 is an end view in which one of the body units and coöperating devices are shown in normal position; Fig. 3 is a transverse sectional view, with some parts broken away, showing a body unit in dumping position; Fig. 3^a is an enlarged sectional view showing the devices for controlling the operation of the body units; Figs. 4 and 5 are detail views illustrating the power operating and controlling mechanism.

1 represents a base frame mounted on trucks 2 and provided upon its forward portion with a driver's cab 3, and a suitable

motor (not shown) for driving the vehicle through the medium of any suitable mechanism. Several brackets 4 are disposed transversely on the base frame 1 (five such brackets being shown in the drawing) and each bracket is provided with a standard 5,—said brackets and the standards thereon being suitably spaced apart to accommodate a plurality of bins or body compartment units 6. The brackets 4 are made approximately A-shaped and are provided at 65 their apexes with bearings for a shaft 7 extending from end to end of the series of brackets, said shaft being thus disposed over the longitudinal center of the base frame 1. This shaft constitutes a support 70 for the compartment body units 6 and on which the latter may turn,—said body units each being provided on its bottom with a bearing block 8 having an elongated slot 9 through which said shaft passes.

Each body unit 6 is provided at each of its ends with a gate 10 hinged at its lower end as at 11, and provided with side flanges 12 which embrace the sides of the bin or unit when closed and which serve as guides for material being discharged when the bin or unit is tilted as shown at the right of Fig. 3. Each gate is retained closed by the engagement of bosses 13 on the sides of the bin or body unit with depressions 14 in the flanges 12 of said gates, and the latter are limited in their opening movement by the engagement of hooks 15 thereon with pins 16 on the body unit as shown in Fig. 3. Each bracket 4 is provided at each end with a bumper 17 to receive the body unit when the same is dumped.

Pivottally connected with the bottom of each body unit between the center and each end thereof, are swinging legs 18 each carrying, at its lower end, a grooved roller 19 normally disposed on the horizontal upper portions 20 of inclined trackways 21. Each trackway has a general V-shape and is disposed transversely of the base frame 1, the ends of said trackway being supported by saddles 22 secured on said base frame midway between brackets 4.

A segmental gear 23 is mounted loosely 105 on the shaft 7 centrally under each body unit 6 and with the ends of this segment the inner ends of links 24 are pivotally connect-

ed, the outer ends of said links being pivotally connected with the legs 18 between the ends of the latter.

The depending portions 25 of the several 5 A-shaped brackets 4 are provided with suitable bearings for a shaft 26, the latter being thus disposed directly under the shaft 7.

Under each body unit, a pinion 27 is located on the shaft 26 and provided with a 10 sleeve 28 and a grooved wheel 29,—all of which elements may be made in an integral structure mounted to slide on the shaft but caused to rotate therewith by means of a spline 30 fixed to the shaft. An arm 31 having a sleeve 32 is loosely mounted upon each sleeve and is provided with a bifurcated depending portion 33 which straddles an arm 34 secured to the adjacent trackway, whereby said arm is permitted to slide with 15 the pinion 27 and sleeve 28 but is prevented from rotating therewith. Each arm 31 carries a pin 35 near its upper end to enter a hole 36 in the adjacent segmental gear 23. When a body unit is in its normal horizontal 20 position, the pin 35 will enter the hole 36 and lock the segmental gear 23 and also the legs 18 in the normal positions shown in Fig. 2 and the pinion 29 will be out of mesh with the segmental gear as illustrated to the 25 left of the center of Fig. 1.

When it is desired to dump one of the body units, it is necessary that the pinion shall be moved into mesh with the segmental gear and that the locking pin 35 shall be 30 withdrawn from the latter, as shown at the left hand end of Fig. 1. To accomplish the shifting of the pinion 27 and the parts movable therewith, a rod 37 is mounted to slide through holes in the track-ways 21 and provided with a spanner arm 38 to engage the grooved wheel 29,—the forward end of said rod being connected with a hand lever 39 located in the cab 3 of the vehicle. A spring 40 is fixed at one end and attached at its 35 other end to the hand lever 39,—said spring thus tending to force the rod 37 rearwardly and cause the locking pin 35 to bear against the face of the segmental gear (after the latter has been moved from its normal position), so that when said segmental gear 40 again arrives at its normal position, the pin 35 will be caused to lock the same and the pinion 27 moved out of mesh with the said segmental gear. Separate shifting devices, such as above described will be 45 provided for the operating mechanism for each body unit (a separate lever 39 being provided in the cab for each set of such shifting devices) so that any one of the body 50 units may be dumped, or so that any group or all of them may be dumped simultaneously.

Any or all of the compartment body units 55 may be dumped or tilted at either side of the vehicle,—the direction of such tilting or

dumping being controlled by the direction of rotation of the driving shaft 26. The shaft 26 may be rotated manually by the application of a suitable crank to the squared end 41 thereof, but we prefer to provide power operated means for driving said shaft, as hereinafter described.

For the purpose of controlling the opening and closing of the gates 10, bars or levers 42 are provided at respective sides of both end portions of each compartment body unit. These bars or levers, may be pivotally connected with the base portions of the brackets 4 or with the base frame 1 and are provided with elongated slots 43, at the lower end of each of which, a notch or offset portion 43a is formed. Pins 45 on the side flanges or wings of the gates are movable in the slots of the bars or levers 42, and the latter are engaged, under certain conditions, by pins 46 of the side flanges or wings of the gates.

When a body unit is to be dumped, the operator will first operate the shifting devices by manipulation of one of the levers 39, and the operating devices will be shifted to the positions shown at the left of Fig. 1. Assume now, that the body unit is to be dumped to the right as shown in Fig. 3. The operator will cause power to the shaft 95 26 to rotate the same to the left and thus cause motion to be transmitted to the segmental gear 26 until the left hand end of the latter engages the bottom of the body unit at the left of the pivotal support of 100 the latter. Continued rotation of the shaft 26 will cause the segment to continue the tilting of the body unit until the latter assumes the position shown in Fig. 3 and is resting on bumpers 17 provided to receive it. 105 During the tilting of the body unit, the roller 19 at the lower end of the right hand leg 18 will run down the inclined trackway 21, and the left hand leg and its roller will be raised, as shown in Fig. 3. As the body 110 unit tilts, the engagement of the lower end walls of the slots 43 in bars or levers 42, with the pins 45 of the wings of the gate, will cause the latter to be forced open until it assumes the position shown at the right 115 of Fig. 3, with the hooks 15 in engagement with the pins 16,—at which time, the bars or levers will drop by gravity so that the pins 45 will become disposed in the notches 43a of said bars or levers and thus the gate 120 will be locked in open position. The contents of the compartment body unit having been discharged, the operator causes the drive shaft 26 to be rotated in the reverse direction to that above described, thus causing reverse motion of the segment 23. This motion of the segment will be transmitted through the right hand link 24 (Fig. 3) the right hand leg 18, causing the roller 19 at the lower end of the latter to ride upwardly 125 130

on the inclined trackway 21 and, by the leverage thus brought into play, the body unit will be raised until it assumes a normal horizontal position,—at which time the 5 spring 40, will actuate the shifting devices as previously described, to lock the segment and move the pinion 27 out of mesh with said segment. During the operations above described for righting the body unit, the 10 engagement of the notched portions 43^a of levers 42 with the pins 45 on the wings of the gate, will cause the latter to be closed and when this has been accomplished, the levers 42 will be engaged by the pins 46 on 15 the wings of the gate so as to raise said levers and release their notched portions from the pins 45. When the body unit has reached its normal horizontal position, the pins 45 will bear the relation to the slots of the levers 42 shown in Fig. 2. It will be apparent that when the body unit tilts in one direction, the pins 45 on the gate at the other end of said body unit, will move freely in the slots of the levers 42.

25 We have described the operations of the devices when a body unit is tilted to the right, as shown in Fig. 3, but it is apparent that when the body unit is to be tilted to the left, the operations above described will be 30 reversed.

It now remains to explain the devices whereby power may be applied to the driving shaft 26, and such devices are operated and automatically controlled.

35 The shaft 26 has keyed thereto, a sleeve 48 (Fig. 4) on which a clutch member 49 is loosely mounted, and to this clutch member, a sprocket wheel 50 may be secured to receive motion from the motor gearing (not 40 shown) which drives the vehicle. Any suitable means may be employed for connecting this sprocket wheel with the motor or its gearing and direction of rotation of said 45 sprocket wheel may be controlled by shifting parts of the motor gearing or reversing the motor, in any well known manner.

A clutch member 51 to coöperate with the clutch member 49 is provided with a hub 52 and keyed to slide on and rotate with the 50 sleeve 48. A bell crank 52 is pivoted to a suitable support and one of its arms is bifurcated and connected with the hub of clutch member 51 in such manner, that when said bell crank is moved, said clutch member 51 will be moved into or out of engagement with the clutch member 49. The other arm of the bell-crank is connected, by means of an adjustable rod 53 with one end of a lever 54 which is pivotally supported between its ends. The other end of the lever 54 is pivotally attached to one end of a lever 55, the latter being pivotally supported between its ends and connected at one end with a spring 56, which latter is maintained 60 always under compression. A block 57 is

secured to the end of the lever 55 to which the lever 54 is connected, and this block is provided with a depending lug 58 having a lateral projection 59.

A gear 60 is mounted loosely on a suitable 70 shaft 61 and meshes with a pinion 62 on shaft 26, from which it receives motion. A disk 63 is secured to the gear 60 and is provided with notches or recesses as indicated 75 at 65, 66 to receive the lug 58. An arm 67 is secured to and depends from the disk 60 opposite the notched portion 65—66 thereof and is provided at its lower end with a V-cam 68 to engage the projection 59 of lug 58 and compel the latter to enter the recessed portion 65—66 of the disk, as presently explained.

A small lever 69 is pivotally supported 80 between its ends, and one arm of this lever engages the lever 55 over the spring 56,— 85 a stop 70 being provided on the lever 55 to prevent the lower arm of lever 59 from being moved far enough to become perpendicular to the lever 55. A rod 71 is connected with the upper arm of the small lever 69 90 and the forward end of this rod is connected with a suitable hand lever in the cab 3.

When any body unit is to be dumped in one direction or the other, the operator will set his motor gearing so as to impart motion 95 to the shaft 26 in the proper direction, and he will also operate the lever connected with the rod 71, for the purpose of actuating the short lever 69 to tilt the lever 55. By this means, the lug 58 on lever 55 will be raised 100 out of the notch 65 of disk 63. The movement of the lever 55, as above described, will cause the lever 54 to be tilted and motion to be imparted through the rod 53 and bell-crank 52 to the clutch member 51 for 105 causing the latter to engage the clutch member 49, and the driving sprocket 50 to be connected with the shaft 26. Motion is now being imparted to the shaft 26 for accomplishing the tilting or dumping of a body 110 unit, and the disk 63 is being slowly turned, with the lug 58 pressing upon its periphery. When the body unit shall have been sufficiently tilted, the notched portion 65—66 of the disk 63 will arrive under the lug 58 and the latter will be forced to drop into said 115 recessed portion of the disk by the pressure of the spring 56 against the lever 55. Should it happen that the operator failed to release the hand lever connected with the 120 rod 71 when the same was operated as above described so that the spring 56 will not now be free to operate the lever 55, engagement of the beveled projection 59 with the V-cam 68 will cause the lug 58 to be forced into the recess of the disk, against any resistance 125 which might be offered by the hand devices which operate the lever 55. When the lug 58 drops into the notched portion 65—66 of the disk, motion will be imparted by 130

movements of the levers 55—54 thus effected, and connections between the lever 54 and the clutch member 51, to remove the latter from the clutch member 49, and thus the operation of the shaft 26 will be automatically stopped when the body unit has been dumped.

It is evident that reversal of the operations above described will cause the body unit to be righted and the operation of the mechanism automatically stopped by the return of the disk 63 and coöperating parts to the positions shown in Fig. 4, when the body unit arrives at or approaches its normal horizontal position.

Various changes might be made in the details of construction of our invention without departing from the spirit thereof or limiting its scope and hence we do not wish to restrict ourselves to the precise details herein set forth.

A beam 72 may be supported over any one of the body units, by means of brackets 73 removably supported in sockets in the upper ends of two of the standards 5. The beam serves to support scales 74 which may be connected with a bail 75, with which each body unit is provided. By these means the contents of each body unit may be separately weighed,—sufficient vertical movement of the body unit for this purpose being afforded by the elongated slot 9 of the bearing block 8.

Having fully described our invention what we claim as new and desire to secure by Letters-Patent, is:—

1. In a dumping vehicle, the combination with a wheeled frame, and a plurality of separate dumping units arranged transversely thereon, of a segment under each unit and loosely mounted independently of the same, means for operating each segment to tilt the body unit over the same when said segment is moved in one direction, and devices connected with the body unit and the segment and coöperating with said segment, a fixed part on the frame and the body unit for restoring the latter when the segment is moved in the reverse direction.

2. In a dumping vehicle, the combination with a wheeled frame and a dumping body unit mounted centrally on said frame and disposed transversely thereof, of a rocking segment mounted independently of the body and adapted at its ends to engage the body unit for tilting the same in one direction or the other, means for imparting motion to said segment, and devices connected with the segment and the body unit and coöperating with a fixed part on the frame for retaining the body unit to normal horizontal position.

3. In a dumping vehicle, the combination with a wheeled frame, and a transversely disposed dumping body unit mounted over said frame, of inclined trackways arranged

transversely on the frame, swinging legs having rollers engaging said trackways, a swinging segment mounted independently and adapted to engage the body unit for dumping the same, connections between said segment and swinging legs, and means for imparting motion to the segment.

4. In a dumping vehicle, the combination with a wheeled frame and a transversely disposed dumping body unit, of hinged end gates for said body unit having side wings, pins on said wings, levers pivotally attached to the frame and having slots to receive the pins on said wings, each lever having a notch communicating with one end of the slot therein, and means for imparting power to said body unit to tilt the same.

5. In a dumping vehicle, the combination with a wheeled frame, and a transversely disposed dumping unit, of mechanism for applying power to said body unit for tilting the same, hinged end gates hinged at their lower edges to the body unit, levers pivoted to the frame and coöperating with the hinged gates to automatically open and close the same, and devices coöperating with the body unit and the gates to limit the opening movement of the latter.

6. In a dumping vehicle, the combination with a wheeled frame, a transversely disposed body unit, and means for applying power to the latter for tilting the same, of end gates hinged to said body unit and provided with side wings to embrace the body unit, levers pivoted to the wheeled frame and disposed parallel with said wings, each of said levers having an elongated slot and a notch at one end of said slot, pins on said wings to enter said groove and notch, and pins on said wings in position to engage said levers to release the notched portions thereof from the first-mentioned pins.

7. In a dumping vehicle, the combination with a wheeled frame and a plurality of dumping units arranged transversely thereon, of segments under the several body units, a shaft, pinions on said shaft to engage said segments and separate hand operated devices for shifting each of said pinions into or out of mesh with its segment.

8. In a dumping vehicle, the combination with a wheeled frame and a plurality of dumping body units, disposed transversely thereon, of a segment under each body unit, a shaft, pinions for said segments mounted to slide on and rotate with said shaft, an arm mounted to slide with each pinion and having a pin to engage and lock the adjacent segment in normal position, and separate manually controlled means for shifting each pinion and arm to engage the pinion with its segment and unlock the latter or to disengage the pinion from the segment and lock the latter.

9. In a dumping vehicle, the combination

with a wheeled frame and a plurality of dumping body units arranged transversely thereon, of a segment under each body unit, a power shaft, a pinion for each segment 5 mounted to rotate with and slide on said shaft, each pinion having a sleeve, an arm mounted on each sleeve, means for guiding said arm in its movements with said sleeve longitudinally of the shaft, a pin on each 10 arm to engage and lock the adjacent segment, a plurality of shifting rods connected respectively with the several pinions, a hand operated device connected with each shifting rod, and a spring for moving each hand 15 operated device and parts with which it is connected in one direction.

10. In a dumping vehicle, the combination with a power driven wheeled frame, and a dumping body unit thereon, of tilting mechanism 20 for said body unit, said tilting mechanism including a power shaft, a clutch for the power shaft comprising a loose and a sliding member, means for applying power to the loose member of the clutch, a pivoted 25 lever, connections between said lever and sliding clutch member, manually controlled means for operating said lever to engage the clutch members, and cam devices for controlling the operation of said lever to re-

lease the clutch members from each other, 30 and gearing between the power shaft and the cam devices for controlling the operation of the latter.

11. In a dumping vehicle, the combination with a power driven wheeled frame 35 and a dumping body unit thereon, of tilting mechanism for the body unit, said tilting mechanism including a power shaft, a clutch on the power shaft and comprising a loose and a sliding member, a pivoted 40 lever, connections between said pivoted lever and the sliding clutch member, a spring-pressed lever with which the first-mentioned lever is connected, a lug carried by the spring-pressed lever, a disk having notches 45 to receive said lug, and manually operable means for moving the spring-pressed lever in a direction to remove the lug thereon from a notch in said disk, and means for operating said disk from the power shaft. 50

In testimony whereof, we have signed this specification in the presence of two subscribing witnesses.
